A. F. JENKINS

CARBIDE HOLDER FOR ACETYLENE GENERATORS

Filed Jan. 15, 1919

Inventor

Alexander F. Jenkins

By

Edwin R. Lamme

Attorney

UNITED STATES PATENT OFFICE.

ALEXANDER FREDERICK JENKINS, OF BALTIMORE, MARYLAND.

CARBIDE HOLDER FOR ACETYLENE GENERATORS.

Application filed January 15, 1919. Serial No. 271,216.

To all whom it may concern:

Be it known that I, ALEXANDER F. JENKINS, a citizen of the United States of America, residing in the city of Baltimore, State of Maryland, have invented certain new and useful Improvements in Carbide Holders for Acetylene Generators, of which the following is a specification.

This application is in part a continuation 10 of that filed by me April 17, 1918, Serial No. 229,109.

The present invention relates to a carbide container or pocket for holding carbide for treatment with water in the generation of acetylene gas, the pocket herein referred to being employed in the same capacity as other carbide pockets known to the art, those shown in the application cited above and in my application, No. 229,107, filed April 17, 1918 and my United States Patent 1,292,327. The various applications referred to relate to carbide holders having perforated tapering pockets, i. e., pockets of downwardly reduced cross-section arranged 25 in staggered and overlapping relation to give uniformity of generation of gas and easy filling and emptying of the pockets. By this arrangement the carbide and ash are conveniently supported, allowing sufficient 30 room for expansion in the consumption of the carbide forming the said refuse or ash which is of a considerably greater volume than the carbide. By uniform generation I mean generation of gas in quantities bearing 35 a substantially uniform relation to the amount withdrawn.

In the various prior applications I have shown pockets of rigid material. These pockets have, as already pointed out, important advantages in that they are easy to empty of the consumed carbide or ash which is inclined to adhere to the pocket, and they afford a large area at the top for support of the ash and liquid. Also the taper of the 45 overlying pockets provides an excessive clearance, making access to the pockets below for filling and emptying easy and convenient.

Along the lines of the development in 50 this art thus defined, I have discovered that

a flexible pocket which may be of separate interlocking members, preferably closed links, or otherwise made completely flexible, offers important advantages. Such a receptacle is adapted for arrangement in accordance with the disclosure of my aforesaid copending applications, in overlapping relation to give generation at uniform pressure and in a high degree to contribute to all the advantages obtained by the various 60 arrangements of tapering pockets outlined in the above-cited applications. But an important advantage, not inherent in the devices thus disclosed, relates to the flexibility of the pocket, making it possible to detach 65 the ash, particularly that which tends to adhere to the walls of the pocket, merely by striking it, thus changing the configuration of the walls of the receptacle and breaking and releasing any encrusted material which 70 may adhere to them.

Another advantage of the flexible pockets is that they may be so made as to render the entire carbide holder reversible, that is, the holder being inverted in the process of 75 emptying the ash, the pockets, relatively speaking, turn inside out and may be filled and operated in this position, avoiding the extra step in the refilling operation which consists in returning the carbide container 80 to upright position after it has been emptied.

In the accompanying drawing I have illustrated a carbide container constructed in accordance with my invention.

Figure 1 is an elevation of a support with chain mesh pockets fragmentarily shown for convenience in illustration.

Figure 2 illustrates my flexible mesh pockets applied to a support composed of 90 separator members.

Referring to the drawing, the carbide container or pocket, which is the subject of my invention, consists of a bag 20 of flexible mesh or separate interlocking members 95 shown in the form of closed or continuous links 21 which compose a fabric termed chain mesh. Each pocket is supported on an open frame 22, preferably of wire or similar material, the edge of the top open-

ing in the bag 20 being secured to the frame in any convenient manner as by having the top links 27 of the mesh material which forms the bag encircle the wire. The frame in turn is adapted to be secured to any kind of a support or upright 23 which may carry one or more pockets in any desired relation. As shown, the pockets overlap.

Referring now to Figure 2, I have illustrated the flexible pocket applied to a support composed of radiating separator members, that is, the carbide holder shown in Figure 2 consists of a series of flexible pockets arranged in staggered and overlapping relation and supported on upright members which preferably act as separators. More particularly, the device illustrated consists of four separators or two intersecting separators or plates 25 arranged at 20 90° or any suitable number of plates at any corresponding angle. Between, on or applied to the plates are supports 26. These are preferably of wire or similar material, but may be otherwise formed, each one being 25 adapted to support the mouth of a chain mesh bag 20 which constitutes the corresponding pocket.

In the form illustrated, which is the preferred construction, the top links 27 of the 30 mesh forming the mouth of the bag or pocket, encircle the wire or similar material forming the frame, and the bag or pocket preferably hangs freely from this frame, not being otherwise secured to the separator plates so that the pocket is free to yield when struck for the purpose of breaking up the ash, and also is free to turn inside out when the carbide holder is inverted in emptying, making it possible to fill the pockets in 40 what may be termed an inverted position and avoid the necessity for returning them to the original or what may be termed the upright position, the whole container being preferably made symmetrical so that the upright and inverted positions referred to are in fact indistinguishable. This feature or advantage is not confined to the pocket illustrated in Figure 2, as the pocket shown in Figure 1 is equally capable of being used in 45 inverted position, and other types of chain carbide pockets may be so constructed.

The manner of using the pocket is obvious to those skilled in the art. It is filled with carbide to which water is applied for generation of acetylene gas by gradual immersion of the carbide in any manner. The mesh permits free entrance of the water and free escape of the water, giving every possible facility for uniform generation or uniform response to the demand, including 55 quick flow of the water to the carbide and quick draining of the water from the carbide, which results in immediate response of the generator to variation in the 60 rate of consumption of the gas by giving a 65

quick pick-up of generation and preventing after-generation. Another and in fact a most important advantage of this type of pocket over those known in the art and described in my copending applications is 70 that already recited, i. e., that the ash which tends to encrust and adhere to the walls of the pocket may be easily broken and released because of the complete flexibility of the pocket, by striking the pocket 75 and changing its form i. e., crushing it. Also, the overhanging pockets because of this flexibility permit easy access to those below for filling, etc.

Having thus described a single apparatus 80 embodying my invention, I desire to have it understood that the specific terms are used in a descriptive sense for the purpose of enabling those skilled in the art to practice the invention and not with the purpose 85 of limiting the scope of the protection to be granted.

What I claim and desire to secure by Letters Patent is:

1. In an acetylene generator a carbide holder, consisting of a flexible pocket of separate interlocking members and supporting means therefor.
2. In an acetylene generator a carbide holder, consisting of a flexible pocket of foraminous material and means for supporting the pocket in distended position.
3. In an acetylene generator a carbide holder consisting of a plurality of flexible pockets of separate interlocking members having inclined walls giving a downward taper, and means supporting the pockets at different levels and in overlapping relation.
4. In an acetylene generator a carbide holder consisting of a plurality of pockets composed of foraminous flexible material, the pockets having a downward taper, and means supporting the pockets in overlapping relation.
5. In an acetylene generator a carbide holder consisting of flexible foraminous pockets and supporting means therefor, the pockets being free to turn inside out when the holder is inverted.
6. In an acetylene generator a carbide holder consisting of flexible foraminous pockets free to turn inside out when the holder is inverted and supporting means therefor, the support being also invertible so that the holder when inverted for emptying, can be filled and used in inverted position.
7. In an acetylene generator a carbide holder consisting of a plurality of pockets composed of flexible foraminous material, and means for supporting the pockets in overlapping relation, said supporting means being in the form of separator members between which the pockets are placed.
8. In an acetylene generator a carbide

holder consisting of a plurality of pockets composed of flexible foraminous material, means for supporting the pockets in overlapping relation, the pockets having a downward taper and being free to turn inside out so the apparatus can be used in inverted position.

Signed by me at Baltimore, Maryland, December, 1918.

ALEXANDER FREDERICK JENKINS.
